(57) **CLAIM**

We claim the ornamental design for a cylinder tube for clamp cylinder, as shown and described.

DESCRIPTION

FIG. 1 is a front elevational view of a cylinder tube for clamp cylinder, the opposite side view being a mirror image; FIG. 2 is a cross-sectional view taken along line 2—2 in FIG. 1

FIG. 3 is a right side elevational view thereof; and,

FIG. 4 is a left side elevational view thereof.

The broken lines shown in FIGS. 1, 3 and 4 are for illustrative purposes only and form no part of the claimed design.
